US00D973549S

(12) **United States Design Patent** (10) **Patent No.:** **US D973,549 S**
(45) **Date of Patent:** **** Dec. 27, 2022**

(54) **VEHICLE EXTERIOR**

(71) Applicants: **Rivian IP Holdings, LLC**, Irvine, CA

(US); **Amazon Technologies, Inc.**,

Seattle, WA (US)

(72) Inventors: **Luke James Mack**, Detroit, MI (US);
Nicholas Adam Malachowski,
Bloomfield Hills, MI (US); **Mohamad
Jeffery Hammoud**, Bloomfield Hills,
MI (US); **Stephen Mark Goodrich**,
Southfield, MI (US)

(73) Assignees: **Rivian IP Holdings, LLC**, Irvine, CA
(US); **Amazon Technologies, Inc.**

(**) Term: **15 Years**

(21) Appl. No.: **29/821,219**

(22) Filed: **Dec. 28, 2021**

Related U.S. Application Data

(63) Continuation of application No. 29/705,730, filed on
Sep. 14, 2019, now Pat. No. Des. 941,710.

CLAIM

The ornamental design for a vehicle exterior, as shown and described.

DESCRIPTION

FIG. 1 is a front corner perspective view of a vehicle exterior showing the claimed design;

FIG. 2 is a front view of the vehicle exterior;

FIG. 3 is a left-side view of the vehicle exterior;

FIG. 4 is a right-side view of the vehicle exterior;

FIG. 5 is a top view of the vehicle exterior;

FIG. 6 is a rear view of the vehicle exterior; and,

FIG. 7 is a rear corner perspective view of the vehicle exterior.

The broken lines and faded sections within the broken lines illustrate portions of the vehicle exterior that form no part of the claimed design.

1 Claim, 7 Drawing Sheets
